United States Patent Office

Des. 217,621
Patented May 19, 1970

217,621

CHEST

James C. Bouffard, High Point, N.C., assignor to Mohasco Industries, Inc., Amsterdam, N.Y., a corporation of New York

Filed Jan. 24, 1969, Ser. No. 15,485

Term of patent 14 years

Int. Cl. D6—01

U.S. Cl. D33—6

The figure is a front perspective view of the chest showing my design.

The side not shown is like the side shown, while the back of the chest is plain and unornamented.

I claim:

The ornamental design for a chest, substantially as shown and described.
